Specification for Design.

Patented Sept. 24, 1912.

Application filed May 29, 1912. Serial No. 700,531. Term of patent 7 years.

● *To all whom it may concern:*

Be it known that I, CHARLES EDWARD GRELLE, a citizen of the United States, and a resident of the city of Portland, county of Multnomah, and State of Oregon, have invented a new, original, and ornamental Design for a Post-Bracket, of which the following is a specification, reference being had to the accompanying drawing, forming part thereof.

The figure of the drawing is a side elevation, in perspective, of a post bracket, showing my new design.

I claim:

The ornamental design for a post bracket, as shown.

CHARLES EDWARD GRELLE.
